UNITED STATES PATENT OFFICE.

KNUT BERGLOF, OF MONESSEN, PENNSYLVANIA.

ANNEALING-FURNACE.

1,336,190.

Specification of Letters Patent.

Patented Apr. 6, 1920.

Application filed May 22, 1918. Serial No. 235,953.

To all whom it may concern:

Be it known that I, KNUT BERGLOF, a subject of the King of Sweden, and resident of Monessen, in the county of Westmoreland 5 and State of Pennsylvania, have invented a new and useful Improvement in Annealing-Furnaces; and I do hereby declare the following to be a full, clear, and exact description thereof.

10 My invention relates to improvements in annealing furnaces.

The objects of my invention are to charge the furnace in one single load, and also to discharge it in one single load, thereby gaining 15 in time of operation, cost of labor, and room occupied for the operation of the furnaces.

I attain these objects by the construction illustrated in the accompanying drawings, 20 which show a combination of two furnaces operated with one charging platform and one conveyer.

Figure 1 is a longitudinal vertical sectional view between a pair of furnaces taken 25 on the line 1—1, Fig. 2, the furnace of the view being partly in longitudinal section taken on line 2—2, Fig. 2; and Fig. 2 is a view transverse to Fig. 1, the left-hand furnace of the view being in cross section taken on the line 3—3, through the chimneys and the right-hand furnace in cross-section 30 in advance of the chimneys on the line 4—4.

The rectangular, brick-line steel-casing 1 supported by the columns 2, 3 and 5, the brick-lined top-cover 6, and the brick-lined bottom-cover 7 constitute the frame-work of each furnace. The casing 1, the top-cover 6 and the bottom-cover 7 are built up of steel- 35 angle and plate girders, the bottom-cover 7 also having steel-plates for supporting the brick lining.

The rectangular casing 1 has the steel-plate springs 8 all around, top and bottom, 45 pressing against the top-cover 6 and bottom-cover 7 when they are closed in order to prevent air from leaking in through the sides during annealing process.

Fuel in the form of a gas and air mixture, 50 or its substitute, is introduced in the furnace through openings 9 in the ends of casing 1 by means of pipes 10.

The top-cover 6 has a gear-rack 11 connected to each end of it in the center and 55 sliding between guide-angles 12 supported by struts 13 and 14 which are connected to

columns 2, 3, and 5, each of said gear-racks 11 engaging a pair of gear-wheels 15 secured to shafts 16 turning in bearings 17, which are supported by struts 13. A compressed-air cylinder 18 is provided for lifting the top-cover 6, said cylinder 18 being supported by strut 19 connected to columns 2 and 3 and having its piston-rod 20 connected to the cover 6. Compressed air is admitted and exhausted through the air-passage 21. The top-cover 6 has two brick-lined chimneys 22, which provide outlets for the fumes.

The bottom-cover 7 is supported on one side by hinges 23 secured to it and to casing 1, and on the other side when closed, is supported by a locking mechanism composed of half-hinges 24 secured to the cover 7, half-hinges 25 secured to casing 1, and rod 26 having pins 27, said half-hinges 24 and 25 engaging each other and locked by said pins 27. Rod 26 slides in grooves in half-hinges 25. By moving the rod 26 longitudinally it will be apparent that the pins 27 carried by said rod will be moved in and out of the half-hinges 24 and 25 so as to lock and release the same.

The lowering and lifting of bottom-cover 7 is executed by compressed-air cylinder 28 supported on foundation 29, having the end of its piston-rod 30 engaged in a half-hinge 31 secured to the cover. Compressed air is inserted and exhausted through air-passage 32.

The charging platform 33 is built up of steel-plates stiffened by steel-angles and supported by a latticed steel strut 34 which has a hinge 35 secured to it at each end at the bottom chord, said hinges being supported by struts 36 connected to columns 2, 3 and 5. A compressed-air cylinder 37 slides on piston-rod 38, the ends of which are secured to casing 1. The cylinder 37 is provided with two projecting pins 39 secured to it and sliding in slots 40 in strut 34. Compressed air is introduced and exhausted through air-passages 41 and 42.

The conveyer consists of pairs of rollers 43, each pair secured to a shaft 44 turning in bearings 45, said shaft 44 having a bevel-gear 46 secured to it at one end, said bevel-gears 46 engaging bevel-gears 48 secured to driving-shaft 47, which is turning in bearings 49. On top of rollers 43 is traveling 105 receiving-vessel 50 built up of channels and angles or some other suitable shapes. Skid-

plates 51 supported by brackets 52 are provided for the annealed material to slide on.

The operation of the furnaces is conducted in the following manner:—The material to be annealed is placed on the charging platform 33. The top-cover 6 is raised by introducing compressed air through air-passage 21 into cylinder 18, said compressed air operating the piston-rod 20 connected to 10 said cover and as the racks rise with the cover said racks turn the gear-wheels 15 secured to shafts 16, thus lifting both ends of the cover simultaneously. The charging platform 33 with the material to be annealed 15 on top of it is now tilted over, turning around hinges 35 by inserting compressed air through air-passage 41 into cylinder 37, thus compelling the cylinder to slide on piston-rod 38 secured to casings 1, said cylinder 37 with its two projecting pins 39 secured to it and sliding in slots 40 in strut 34, thus tilting the platform, as shown in dotted lines, and dumping the material to be annealed into the furnace. The compressed air is now discharged from the cylinder through passage 41 and introduced into it through passage 42, the platform 33 thus being raised up in the same way as it was tilted. After top-cover 6 is lowered by 20 letting the compressed air out of the cylinder 18 through passage 21, annealing takes place in usual way. The annealing being accomplished, compressed air is introduced into cylinder 28 through passage 32, lifting the 25 bottom cover 7 a trifle, thus enabling a man to push pins 27 secured to rod 26 out of half-hinges 24 and 25 letting the cover loose to be swung around hinges 23 by slowly letting the compressed air out of the cylinder, the annealed material falling down 30 on skid 51 and into receiving-vessel 50, which is carried away on conveyer rollers 43. The bottom-cover is closed in a similar way as it was swung down and the operation 35 of the furnace can be repeated.

What I claim is:

1. In an annealing furnace, the combination with the sides, end-walls and bottom, of a vertically movable top, and means for 50 lifting the same to a height whereby the

material may be charged into said furnace between the raised top and the sides.

2. In an annealing furnace, the combination with the side, end-walls and bottom, of a movable top, a rack-bar carried by said top, means for raising and lowering said rack-bar, and pinions supported above the top engaged by said rack-bar. 55

3. In an annealing furnace, the combination with side, end-walls and bottom, of a movable top, a rack-bar connected to said top, pinions above said top engaged by said rack-bar, a fluid-operated cylinder, and a piston connected to said rack-bar. 60

4. In an annealing furnace, the combination with the side, end-walls and bottom, of a movable top, rack-bars connected to opposite ends of said top, shafts supported above said top, pinions on said shafts engaging said rack-bars, and means for raising and 70 lowering said rack-bars. 65

5. In an annealing furnace, the combination with the side, end-walls and bottom, of a movable top, means for lifting same, and a tilting charging device at the side of said 75 furnace adapted to discharge the material through the top of the furnace.

6. In an annealing furnace, the combination with the side, end-walls and bottom, of a movable top, means for lifting same, a 80 tilting charging member, a hydraulic cylinder, and connections between said tilting member and said hydraulic cylinder whereby the material is charged through the top opening of the furnace. 85

7. In an annealing furnace, the combination with the side, end-walls and bottom, of a movable top; means for lifting same, a charging device comprising a strut pivotally-mounted at its lower end, a cradle carried by said strut, a stationary piston-top, a cylinder adapted to move on said rod, and connections between said strut and said cylinder. 90

In testimony whereof I, the said KNUT BERGLOF, have hereunto set my hand.

KNUT BERGLOF.
